UNITED STATES PATENT OFFICE

EARL C. WALKER, OF CHICAGO, ILLINOIS, ASSIGNOR TO INTERNATIONAL HARVESTER COMPANY, A CORPORATION OF NEW JERSEY

CONDENSER SYSTEM FOR RAIL CARS

Application filed February 7, 1930. Serial No. 426,522.

This invention relates to a condenser system for steam rail cars or buses. More particularly, it relates to the position of the units of a condenser system and to means for circulating air therethrough.

The object of the invention is to provide an air-cooled condensing system of sufficient capacity for a continuous maximum load on a steam power plant particularly designed for driving a rail car.

Another object is to position the units of the condensing system on a rail car so as to obtain the maximum benefit of the air draft produced by movement of the car.

Another object is to provide means for varying the condensing capacity as desired by cutting out one or more of a series of air circulating fans.

Other objects will be apparent from the detailed description to follow.

The objects of the invention are accomplished by the construction and arrangement of elements as shown in the drawings, in which:

Figure 1 is a side elevation showing diagrammatically the front end of a steam driven rail car, in which a condenser system illustrating the invention is employed;

Figure 2 is a front elevation end view of the car shown in Figure 1;

Figure 3 is a cross section taken on the line 3—3 of Figure 2;

Figure 4 is a top plan view of the car shown in Figure 1; and,

Figure 5 is an enlarged section showing one of the controls in the condenser unit outlets.

As shown diagrammatically, the rail car is provided with a steam driving engine 1 connected by a drive shaft 2 to one of the axles of the truck 3. A boiler, not shown, is located in the car in a compartment covered by the door 4 at the front of the car. An auxiliary steam engine, which is also mounted at the front end of the car, is not shown, as it

is not a part of this invention. The power plant is of the condensing type, in which the exhaust steam from the engines is condensed and re-used as feed water with the loss of comparatively little water.

Exhaust steam from the engine 1 is delivered through an exhaust pipe 5 to the top of the car where the condensers are located. If the car is driven by two engines, the exhaust from one may be delivered to one side of the car and the exhaust from the other to the opposite side. In any case, a pressure equalization pipe 6 is connected across the main intake pipes 7 positioned along the sides of the car above the condenser units 8. As shown, there are eight condenser units on each side of the car. The units are tilted inwardly at the top, as shown in Figure 2. At the front of the car a series of units 9, exactly similar to the units 8, are positioned vertically. A distributor and pressure equalizer pipe 10 extends across the front of the car joining the main distributor pipes 7. As shown in Figure 3, an inlet connection 11 joins the header of each of the condenser units 9 to the distributor pipe 10. Although not shown in the drawings, each of the condenser units 8 is similarly connected to the adjoining sections of the distributor pipes 7.

The top of the car between the banks of condenser units is closed by a cover 12. Three large circular openings 13 are provided in the cover 12 for the fans 15 and as outlets for air drawn through the condenser cores. The cover 12 together with the banks of condenser units form an air circulating chamber.

The interior of the chamber is divided by partitions 14 into three compartments 14.

Each of the compartments 14 contains a circulating fan 15, which is positioned below the opening 13 in the cover 12. A motor driven shaft 16 extends longitudinally through the three compartments. In each compartment a clutch 17 and bevel gears 18

and 19, mounted respectively on the shaft 16 and on fan shafts 20, provide means for driving the fans 15. The shaft 16 is adapted to be driven by an electric motor 21 located back of the rear compartment.

As shown diagrammatically, the clutches 17 are adapted to be remotely and independently operated by fluid pressure-cylinders bellows or "sylphons" 22. Individual pipes 23 lead from each control cylinder or sylphon to a position adjacent the operator's position in the car where valves for admitting or releasing fluid pressure in pipes 23 are located.

Around the openings 13 in the cover 12 a narrow shroud 24 is positioned to aid in the flow of air through said openings when the car is in motion.

On the faces of the side condenser units 8 deflectors 25 are positioned with their outer edges extending forwardly in the normal direction of movement of the car for the purpose of deflecting the air stream created by the movement of the car, through the condenser cores.

As shown in dotted lines in Figures 1 and 2, a condensate collecting system communicates with the lower header of each of the condensing units. Longitudinal pipes 26 extend along the bottom of the condenser units downwardly toward an intermediate point where they join with a transverse pipe 27 leading across the car. At the front of the car a transverse condensate pipe 28 connects with each of the outlets of the condenser units 9. The transverse pipes 27 and 28 discharge into a vertical pipe 29 leading to a hot well which delivers to the feed water pump for the boiler. These elements comprise a part of the steam generating system, not shown, as it is not a part of this invention.

As shown in the enlarged detail of a condenser unit (Figure 5) means are provided for preventing the flow of steam from the condenser units into the condensate lines. In the lower header 30 of a condenser unit a cage 31 is mounted interiorly thereof. A valve element 32 is secured to a temperature operated, expandible element 33. The element 33 is in turn secured to the cage 31. The valve 32 seats in an outlet opening in the fitting 34 mounted on the header wall. A condensate pipe 35 is connected to the fitting 34. Openings 36 are provided at the bottom of the cage 31 for fluid flow therethrough.

In the operation of this condensing system, exhaust steam is delivered through the risers 5 to the main distributor pipes 7. The pressure equalization pipe 6 maintains a substantially equal pressure in the distributor pipes 7. Steam is delivered to each of the condenser units 8 and, by means of the transverse distributor pipe 10, to the condenser units 9. The condensate collecting at the bottom of the condensing units flows by

gravity in the collecting pipes 26, 27, 28 and 29 to the hot well of the steam generating system.

The motor 21 is put into operation and the fans 15 draw air inwardly through the condenser units and force it up and out through the openings 13. During normal operation of the car, a substantial air pressure is produced at the front of the car. Such a pressure creates a draft through the front condenser units 9 and out through the front opening 13. It may, therefore, be found desirable to disengage the clutch 17 operating the front condenser fan, as sufficient condensing capacity may be available without the use of this fan. When operating at light loads or in cold weather, it may be found that sufficient condensing capacity is available with two or all of the fans disconnected. The clutch operating mechanism, being controlled by the pressure operated bellows, may be thrown in and out of engagement, as found desirable, by the operator of the car.

In the drawings and description of this invention, I have shown diagrammatically one form in which the invention may be embodied. It is to be understood that any variations or modifications, in which the principles of the invention are embodied, are contemplated. Applicant, therefore, limits his invention only by the scope of the appended claims.

What is claimed is:

1. In a steam rail car, a series of condenser units positioned at the top of the car along the sides thereof, an exhaust steam distributor pipe communicating with each of said units, means for collecting the condensate from each of said units, said means including means for removing condensate therefrom and preventing the flow of steam, means cooperating with said units to form an air circulating chamber, an opening in said means, and a fan positioned in said opening and adapted to create a current of air through the condenser units and through said opening.

2. In a steam rail car, a series of condenser units positioned at the top of the car along each side thereof, an exhaust steam distributor pipe communicating with each of the units, condensate outlets from each of the condenser units, each outlet having temperature operated means therein adapted to prevent the flow of steam therefrom, means for collecting the condensate from each of said units, means cooperating with said units to form an air circulating chamber, an opening in said means, and a fan positioned in said opening and adapted to create a current of air through the condenser units and through said opening.

3. In a steam rail car, a series of condenser units positioned at the top of the car along each side thereof, means for distributing ex-

haust steam to each of said units, means for collecting the condensate from each of said units, a cover cooperating with the condenser units to form an air circulating chamber, partitions dividing said chamber into a plurality of compartments, an opening in the cover in each compartment, a fan positioned in each opening and adapted to deliver air therefrom, and remotely controlled means for independently operating each of said fans.

In testimony whereof, I affix my signature.
Chicago, Illinois, January 16, 1930.

EARL C. WALKER.
